UNITED STATES PATENT OFFICE

ARTHUR GAUDENZI, OF BADEN, SWITZERLAND, ASSIGNOR TO AKTIENGESELLSCHAFT BROWN BOVERI & CIE., OF BADEN, SWITZERLAND, A JOINT-STOCK COMPANY OF SWITZERLAND

ARRANGEMENT FOR REDUCING THE VAPOR MASS ABOUT THE ANODES OF MERCURY VAPOR DIRECT CURRENT RECTIFIERS

Application filed September 19, 1928, Serial No. 306,867, and in Germany September 21, 1927.

This invention relates to means for preventing the accumulation of large masses of vapor about the anodes of an electric current rectifier of the mercury arc type.

5 Large vapor masses become dangerous to continued operation of such rectifiers, for the reason that mercury may condense on the anodes and form a cathode spot which results in backfiring with its attendant disturbance 10 to connected apparatus and damage to the rectifier itself. The accumulation of mercury vapor is usually due either to defective cooling or to complete failure of the cooling system, which permits formation of dangerously 15 high vapor pressures. Various means have been unsuccessfully proposed for the elimination of this discharge.

It is, therefore, among the objects of the invention to provide means for preventing the accumulation of masses of vapor about the anodes of a mercury vapor electric current rectifier to prevent such accumulations from becoming dangerous to the continued operation of such rectifiers.

25 A further object of the invention is to provide a special chamber about the anodes of a mercury arc electric current rectifier whereby accumulations of vapor masses thereabout are prevented.

30 Other objects and advantages will hereinafter appear in the description and the drawings in which for purposes of illustration only, an embodiment of the invention is shown, and wherein the figures are schematic representations of rectifier structures taken on a central plane therethrough, in which

Fig. 1 shows the invention embodied in a glass enclosed rectifier; and

Fig. 2 shows the invention embodied in a 40 rectifier of the usual metallic construction suitable for large outputs.

Referring more particularly to the drawings by characters of reference: 5 indicates the anodes of a mercury vapor electric current rectifier formed of glass. The anodes 5 are disposed in arms 6 extended outward from the sides of the main portion of the rectifier. The arms 6 may be formed horizontally with upwardly extending ends, as shown, or may be disposed at an angle to the main portion

of the rectifier. It will be understood that the cross sectional area of the arms 6 need not be uniform throughout their length, but may be constricted at various points, or may be decreased equally along the length thereof. Radially extending arms 7, arranged below the arms 6, contain the ignition anodes 8. A mercury cathode 9 is provided at the lowest point of the main chamber.

45 A plurality of radially, outwardly extending arms 10 are formed between the arms 7 and the cathode 9. These arms form expansion and condensation chambers for the mercury vapor produced during the operation of the device. It will be understood that the arms 10 need not be arranged at right angles to the surface of the rectifiers, but may be arranged at any angle thereto. Instead of being formed with the arms 10, the rectifier may be formed with an outwardly extending, circular enlargement which will perform the same function as the arms 10. Any excess mercury not condensed by the usual condensing dome 11, will enter the arms 10 and be condensed therein. It will be understood 50 that the rectifier may be formed with cooling fins or any other devices for increasing the cooling surface and that a fan, or any other suitable means, may be used for increasing the radiation of heat therefrom.

55 The invention as applied to rectifiers formed of metal includes the usual double wall container 15, formed with a cathode well 16, in the bottom thereof, for receiving the mercury forming the cathode. The container 15 is closed by a top 17, through which the usual anodes 18 extend and which are supported by the top in a well known manner. The reference character 19 indicates the usual mercury vapor condensation dome located on the top 17 and in communication with the interior of the condenser 15. The lower end of the dome 19 extends into the container 15 and is formed with an inwardly and upwardly turned flange which forms a trough in which the mercury condensed in the dome gathers and from which it is discharged through the dependent tubes 20. The dome may be of double wall construction provided with cooling coils, as shown, or of any other

construction suitable for providing contact between the mercury vapor within the dome and the cooling means arranged therewith.

A partition member 21 is secured in depending relation to the top 17 in either insulating or conducting relation therewith. The member 21 is, generally, circular in shape and of such diameter that the anodes 18 are enclosed thereby and that an annular space is defined between the walls of the member 21 and the exterior walls of the chamber 15. A portion 22 of the bottom of the member 21 is downwardly inclined in a conical manner and is bent near the apex of the portion 22 into approximately the form of an upwardly extending frustum of a hollow cone 23. The portions 22 and 23 of the partition member 21 forms a collecting basin for condensed mercury which is discharged therefrom to the bottom of the chamber 15 through the apertures 24.

The tubes 20, depending from the collecting trough of the dome 19, discharge into the apertured collecting basin formed by the bottom portions 22 and 23. The upper end of the bottom portion 23 extends into close proximity with the lower end of the dome 19, forming a partially enclosed passageway whereby the greater portion of the mercury vapor is conducted into the dome and is condensed therein.

It will be seen that the annular space formed by the circular wall of the partition member 21 and the wall of the container 15 forms a separate condensation chamber closed off from the anodes 18, wherein the excess mercury vapor formed during the operation of the rectifier is condensed and flows back to the cathode well 16.

Although I have illustrated only a few embodiments of the invention, it will be apparent to those skilled in the art that it is not so limited but that various modifications and changes may be made therein, without departing from the spirit thereof or from the scope of the appended claims.

What I claim is:

1. An electric current rectifier of the mercury arc type comprising an external casing, 50 anodes within said casing, a mercury cathode within said casing, a mercury condensing chamber in the upper portion of said casing having walls extending thereto, said walls being formed to provide a mercury collecting trough at the lower portion thereof, a partition member dividing said casing into a plurality of chambers, one of said chambers forming an auxiliary condensing chamber for mercury vapor therein, and tubes for discharging mercury from the collecting trough of said upper condensing chamber upon the bottom of said partition member.

2. An electric current rectifier of the mercury arc type comprising an external casing, 65 anodes depending into said casing from the

top portion thereof, a cathode within said casing, a chamber in communication with the upper portion of said casing for condensing mercury vapor therein, and a partition member having a wall enclosing said anodes and having a bottom wall provided with a central opening for passage of vapor from said cathode into said chamber, the upper edge of said first-named wall being in contact with said casing, said partition member forming an auxiliary vapor condensing chamber with the outer wall of said casing, said bottom wall having a conical portion inclined downwardly from the outer wall of said partition member and having a centrally disposed conical portion extending upwardly, said bottom portions forming a collecting basin for mercury.

3. An electric current rectifier of the mercury arc type comprising an external casing, 85 anodes depending into said casing from the top portion thereof, a cathode within said casing, a chamber in communication with the upper portion of said casing for condensing mercury vapor therein, and a partition member having a wall enclosing said anodes and having a bottom wall provided with a central opening for passage of vapor from said cathode into said chamber, the upper edge of said first-named wall being in contact with said casing, said partition member forming an auxiliary vapor condensing chamber with the outer wall of said casing, said bottom wall having a conical portion inclined downwardly from the outer wall of said partition member and having a centrally disposed conical portion extending upwardly, said bottom portions forming a collecting basin for mercury, said bottom wall having perforations adjacent its lowest portion for the passage of mercury.

In testimony whereof I have hereunto subscribed my name this 28th day of August A. D. 1928.

ARTHUR GAUDENZI.
